UNITED STATES PATENT OFFICE.

THOMAS P. KIRKPATRICK, OF WILKINSBURG, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed October 4, 1922. Serial No. 592,248.

My invention relates to motor-control systems, and it has special relation to the control of motors for driving loads having unusually heavy fly-wheel effects, such as 5 the spinning wheels of gyroscopes.

One object of my invention is to maintain substantially constant torque of the spinning motor during the accelerating period.

Another object of my invention is to prevent over-loading the motor during acceleration.

A further object of my invention is to accomplish the necessary control automatically and with increased efficiency relative to 15 methods of the prior art.

The power system for operating the spinning wheel of a gyroscope usually comprises a turbine-driven generator for supplying power to an induction motor that is connected to the driving shaft of the spinning wheel. On account of the very high inertia, it is necessary to accelerate the spinning motor very slowly. A scheme has been adopted in which the spinning motor is connected to the generator when at rest, and steam is gradually admitted to the turbine to start the motor with a minimum impressed voltage and frequency. The voltage and frequency of the generator are gradually increased to normal as the turbine speed increases. Manual control has been employed during the entire accelerating period, which in some instances, consumed approximately two hours. During this period, it is desirable to maintain a substantially uniform power in-put into the motor with, however, a slight increase of power at low speeds.

The operator employs the ordinary instruments for measuring input and it will be recognized that, at low frequency, these instruments are unreliable.

I propose to employ a relay responsive to the motor current for automatically controlling the throttling valve of the turbo-generator. The throttle is preferably motor-operated, the operating motor being controlled by means of a reversing switch, whereby the steam flow is suitably regulated.

Experience has shown that, at low frequency, it is necessary to supply an accelerating current of somewhat higher value than is required at high frequency. In order to properly control the current, I provide a

suitable condenser or capacity device in series relation with the operating coil of the relay, and preferably connected to a "shunt" or resistor in series relation with the spinning-motor circuit, the relay coil and condenser being in shunt relation to the resistor.

The relay is responsive to the current traversing the main circuit. At low frequency, the condenser has a higher impedance to the passage of alternating current than at normal frequency, and the relay coil therefor absorbs current in proportion to the frequency. The motor-operated throttle-valve is automatically controlled by the relay so as to permit a slight increase in the amount of steam admitted to the turbine 70 during the early portion of the accelerating period.

My invention will be described in connection with the accompanying drawing, in which

Fig. 1 is a diagrammatic representation of circuits and apparatus embodying my invention, and

Fig. 2 is a diagrammatic representation of the relations of current and torque in connection with the system of Fig. 1.

Referring particularly to Fig. 1, a spinning or a fly-wheel 1 of a gyroscope is directly connected to a spinning motor 2 of the induction type, which is supplied with current from a suitable generator 3; the generator is driven by means of a turbine or other suitable source of power 4.

Steam or other fluid, under pressure, is admitted to the turbine 4 through a throttle valve 5 which is actuated by a motor 6. A relay 7, having an operating coil 8, controls the direction of rotation of the motor 6. A condenser 9 is connected, in series relation with the coil 8, and both are disposed in shunt relation to a resistor 10 which is connected in circuit with the spinning motor 2. The motor 6 is supplied with power, from an auxiliary circuit comprising conductors 11 and 12, through a control switch 13.

Assuming the apparatus to be in the inactive or illustrated positions, in which the throttle valve 5 is presumed to be closed, the control switch 13 may be closed to admit current to the motor 6 through the relay 7 in its lower position. The motor 6 is so con-

nected as to gradually open the valve 5 and admit fluid pressure to the turbine 4. The generator 3 begins to furnish power to the spinning motor 2 and, at a predetermined value of current traversing the operating coil 8, the relay 7 "picks up", interrupting the circuit of the motor 6. If the accelerating current continues to rise, the relay 7 will be lifted to its upper position to reverse the direction of rotation of the motor 6 and partially close the valve 5.

When the value of the accelerating current is sufficiently decreased, the relay 7 again disconnects the motor 6 and, if insufficient power is then supplied to the motor 2, the relay 7 is returned to its lower position to reconnect the motor 6 for a sufficient period of time to admit a greater supply of fluid-pressure to the turbine.

At low generating speed, and correspondingly low frequency, the condenser 9 provides a high impedance to current traversing the relay coil 8, whereas, at higher frequencies, less impedance is offered to the passage of current. Therefore, as the spinning motor 2 approaches its normal speed, the relay 7 becomes more sensitive and picks up at a lower value of current. Consequently, the motor 6 "throttles" the fluid-pressure to a minimum value for which the controlling apparatus has been adjusted. It is evident that the coil 8 may be arranged to operate at any desired current value and that the condenser 9 may be selected of suitable capacity to accomplish the desired operation.

With reference to Fig. 2, the curve A represents the relation of accelerating current to motor torque at low frequency, and curve B represents the relation of accelerating current and torque at high frequency, for a given "capacity", of the condenser 9.

It is apparent from the foregoing description that an automatic system of the character described may be made much more efficient and effective than a system employing manual control. With my system of control the power apparatus may be of less capacity, with a corresponding decrease in cost, as compared to non-automatic systems in which the power input is of uncertain quantity. Other systems of power supply, such as motor-generator sets and rotary-converters, may be used instead of a steam-driven unit. In such cases, a relay may be arranged to control the field strength of the motor or "rotary" converter in a manner correspond-

ing to the control employed for the throttle valve in the system that I have described.

I claim as my invention:

1. In a system of acceleration for fly-wheels, the combination with a fly-wheel and a driving motor therefor, of a variable speed alternating-current generator for supplying power to the motor, means for controlling the generator to supply a high accelerating current to said motor at low generator speed and automatically operable means for controlling the generator to supply a lower current to said motor at a higher speed.

2. In a system of acceleration for fly-wheels, the combination with a fly-wheel and a driving motor therefor, of a variable speed alternating-current generator for supplying power to the motor, means for controlling the generator to supply a high accelerating current to said motor at low generator speed and means comprising a relay responsive to an increase in frequency of the generator for reducing the value of the current supplied to said motor.

3. In a system of acceleration for fly-wheels, the combination with a fly-wheel and a driving motor therefor, of a variable speed alternating-current generator for supplying the motor, means for controlling the generator output and means responsive to a change in the frequency of the generator for varying the setting of said control means to further control the generator output.

4. In a system of acceleration for fly-wheels, the combination with a fly-wheel and a driving motor therefor, of a variable speed alternating-current generator for supplying power to the motor, current limiting means for controlling the generator output and a capacity device for automatically varying the setting of said current limiting means in response to a change in the frequency of the generator current output.

5. In a system of acceleration for fly-wheels, the combination with a fly-wheel and a driving motor therefor, of a variable speed alternating-current generator for supplying power to the motor, current limiting means for controlling the generator output and means responsive to a change in frequency of the generator for effecting a change in the operation of said current limiting means.

In testimony whereof, I have hereunto subscribed my name this second day of October, 1922.

THOMAS P. KIRKPATRICK.
